EUGENE WILSON YEARSLEY, OF BROOKLYN, NEW YORK, ASSIGNOR TO OTIS ELEVATOR COMPANY, OF NEW YORK, N. Y., A CORPORATION OF NEW JERSEY

TEMPERATURE COMPENSATOR

Application filed July 31, 1930. Serial No. 471,944.

The invention relates to control systems and especially to control systems for elevators.

In apparatus of this character, especially in high speed elevator installations, one of the problems that has been experienced is to secure uniform operation of the elevator car. The temperatures of the electrical apparatus, in particular such units as the elevator hoisting motor and, in installations employing the Ward Leonard system of control, the motor generator set, vary considerably due to service conditions. The electrical apparatus is usually comparatively cold when the elevator is put in service in the morning and heats up to a maximum at some time during the day and then cools down when the elevator is partially or wholly put out of service. The changes in temperature of the windings of the drive units cause changes in the operating performance of the elevator. The changes in temperature of certain control apparatus may also affect the operating performance of the elevator. These changes in performance have been particularly noticeable in certain installations in which automatic stops are made and in certain installations in which self-levelling is employed.

The principal object of this invention is to obviate the effects of temperature changes and insure uniform operation of the elevator car.

One feature of the invention is to obtain uniform operation of an electrical drive unit regardless of the heating of its windings.

Another feature of the invention is to obtain uniform operation of an elevator car operated by a combination of drive units, regardless of the heating of the windings of such units, by controlling the field strength of one or more of said units.

Another feature of the invention is to obtain uniform operation of an elevator car by controlling the operation of the switching mechanism which controls retardation and acceleration of the car in such manner as to compensate for changes in temperature in one or more of the drive units or of the switching mechanism itself.

Other features and advantages will become apparent from the following:

The invention involves the controlling of the strength of the magnetic field of an elevator drive unit or control unit or both or of a plurality of either or both of such units in such manner as to compensate for variations in temperature which affect the operation of the elevator car. More specifically, the invention involves the controlling of the strength of the magnetic field of such unit or units by employing resistance electrically connected with the winding or windings thereof and varying the value of resistance in accordance with the changes in temperature.

For the purpose of illustrating the genus of the invention, a typical concrete embodiment is shown in the accompanying drawings in connection with a Ward Leonard system of control.

In the drawings:

Figure 1 is a schematic representation of an elevator installation illustrating the adaptation of the invention to a plurality of elevators;

Figure 2 is a simplified schematic diagram of the power and control circuits for one elevator;

Figure 3 is a diagrammatic representation of the control panel for one elevator, illustrating the relation of the coils and contacts and other component parts of the switches employed in the control system; and

Figures 4, 5 and 6 are diagrammatic views illustrating further applications of the invention.

Referring to Figure 1 in which the various parts of two elevator systems are indicated by legend, the elevator car and counterweight of elevator No. 1 are raised and lowered by the elevator motor. The hoisting cables are connected to the car and counterweight and pass over the hoisting sheave in accordance with the principles of the traction drive. The compensating cables are connected to the bottom of the car and counterweight and are illustrated as being tensioned by a compensating sheave. The elevator motor is of the direct-current type and is supplied with current at a variable voltage by a direct-current

generator in accordance with the principles of the Leonard system. The driving means for the generator is preferably an electric motor, and may be of either the direct-current or 5 alternating-current type.

The temperature compensating mechanism for elevator No. 1 is mounted on the control panel for that elevator. The details of this mechanism are not illustrated in this figure 10 and will be described later. Briefly, however, this mechanism comprises temperature responsive elements placed so as to be subject to the temperature of the drive or control unit for which it is desired to provide 15 compensation or which is to be utilized to effect compensation and connected to compensating mechanism on the control panel. According to the embodiment chosen for purposes of description, bulbs containing expandable fluid are employed as the temperature responsive means and these bulbs are 20 connected to the compensating mechanism by tubes.

This arrangement is indicated schematically 25 for effecting compensation for variations in temperature of windings of the elevator motor and its supply generator by connecting tubes leading from each of these units to the control panel. This showing is simply illustrative for the principles of the invention 30 are applicable to other parts of the system as will be shown by later description.

Inasmuch as in most elevator installations in which more than one elevator car is employed to serve the building and particularly in the case of elevators in a group, the elevators are usually placed in service in the mornings and discontinued from service in the evenings about the same time and average 35 about the same in the amount of operation, the temperature compensating mechanism for one elevator may be employed to effect compensation for units of the other elevators. Such arrangement is illustrated in 40 Figure 1 for two elevators, it being understood that the mechanism may be employed for more than two elevators so long as the operating conditions for the elevators remain substantially the same. The connection of the 45 temperature compensating mechanism for elevator No. 1 to the compensating control switches for elevator No. 2 is indicated in Figure 1 by a conduit which extends between the control panels and through which the 50 connecting wires extend. On the other hand, each elevator may have its own compensating mechanism, if desired.

The control panel for elevator No. 1 with its various switches is illustrated in Figure 60 3. No description of the switches or the panel will be given at this time, as it is believed that their construction and operation will be sufficiently understood from the description which follows.

65 Reference may now be had to Figure 2

which illustrates diagrammatically the various control and power circuits. In this figure, the coils and contacts of certain of the electromagnetic switches are not shown in their associated positions, a simplified diagram being employed wherein the coils and contacts of these particular switches are separated in the interest of simplification of circuits. The relation of the coils and contacts may be seen by reference to Figure 3. 70 For a clearer understanding of the invention, the stationary contacts of the switches are illustrated in cross-section.

The various electromagnetic switches employed in the control system chosen to illustrate the principles of the invention are designated as a whole as follows:

A—Potential switch
 B—Up direction switch
 C—Down direction switch
 E, F—Accelerating switches
 G—Maintaining relay
 H—Brake switch
 J—Minimum current field relay
 K—Driving motor starting switch
 L—Driving motor running switch
 M—Driving motor starting relay
 N, O, P—Generator field compensating 90 relays
 Q, R, S—Elevator motor field compensating relays
 T, U, V—Accelerating mechanism compensating relays
 Z—Speed regulating switch

The letter X is employed to designate an inductance coil.

Throughout the description which follows, these letters, in addition to reference numerals, will be applied to the parts of the above designated switches. For example, B 119 will indicate that the contacts are on the up direction switch, while operating coil A 53 will indicate that the coil operates the potential switch. This will be made clear by reference to Figure 3. In the case of the numerals employed in the control system, the lowest number "20" appears in the upper left-hand corner of Figure 2 with the succeeding numbers following in numerical sequence from left to right, downwardly of the sheet of drawings. The arrangement of the numerals in this sequence facilitates the ready location of any element referred to in the description. The electromagnetic switches are shown in their deenergized positions.

The driving motor of the motor generator set is illustrated as of the alternating current type. The stator windings are designated 164, 165 and 166 and the rotor is designated 167. The generator driven by the driving motor is of the variable voltage direct current type. The armature of the generator is designated 127, its separately excited field winding 123 and its series field winding 126. The series field winding 126 may have any 120

desired number of turns to effect the desired compounding of the generator to compensate for variations in load. The driving motor also drives an exciter for supplying current 5 to the separately excited field windings of the elevator motor and generator and also to the operating coils of various control switches. The armature of the exciter is designated 22, its shunt field winding 21 and its series field 10 winding 20. The armature of the elevator motor is designated 128 and the separately excited field winding of the elevator motor is designated 23.

Accelerating resistances 156, 157 and 158 15 are provided for the driving motor. Resistance 117 is provided for controlling the voltage applied to the generator separately excited field winding 123. Resistance 117 is arranged in steps to be controlled by the accelerating switches to bring the generator voltage up to full value. Resistance 32 is provided for controlling the voltage applied to the elevator motor field winding 23.

In addition to resistance 117, a resistance 25 118 is provided for controlling the voltage applied to the generator field winding 123. Resistance 118 is also arranged in steps to be controlled by compensating relays N, O and P subject to the control of the temperature 30 compensating mechanism unit for the generator field winding. Similarly, an additional resistance 83 is provided for controlling the voltage applied to the elevator motor field winding 23. This resistance also is arranged in steps to be controlled by compensating relays Q, R and S subject to the control of the temperature compensating mechanism unit for the elevator motor field winding. Additional compensating resistances 69 35 and 85 are provided for the accelerating switches E and F, resistance 69 being connected in series with the actuating coils of these switches while resistance 85 is adapted to be connected in a discharge circuit for 40 the coil of accelerating switch E.

The temperature compensating mechanism employed is illustrated as three separate units, one for the elevator motor field winding 23, another for the generator field winding 123 and the remaining one for the accelerating switches. These units are illustrated only diagrammatically and their construction may vary considerably from that indicated in the drawings. Referring to the compensating mechanism unit for the elevator motor field winding, for example, this unit comprises a pivoted switch lever 36 provided with a contact segment 41 on its outer end. Stationary contacts 44, 43 and 42 are positioned to be engaged by contact segment 41 as movement of lever 36 about its pivot is effected. The lever is actuated by a bellows device 40 which is connected to the lever by a slot and pin connection. A spring 39 is provided for biasing the contact lever into

position in which its segment 41 is disengaged from its stationary contact. An adjusting screw 38 regulates the pressure of this spring and thus affords an adjustment for the initial operating point of the unit. 70 The bellows device 40 is connected by a tube 35 to a bulb 24 illustrated as arranged in the field winding 23. The actual location of bulb 24 in the elevator motor may be varied, it being understood that any location is suitable so long as the bulb is subject to temperature of the motor, particularly to the temperature of the field winding. The bulb, connecting tube and bellows device, contain fluid 75 of a type such as will expand due to increase in temperature. Oil may be found suitable for this purpose. The bulb 124 for the compensating unit for the generator field winding is similarly located in the generator so as to be subject to temperature changes. The bulb 78 of the unit for the accelerating switches is positioned to be subject to the temperature of one of the switch coils and may be located within the coil itself as illustrated 80 in Figure 3.

The various safety switches, limit switches and door and gate contacts may be employed, some of which have been omitted for convenience of description; others will be referred to in connection with the description 85 of the various circuits and in connection with the operation of the system.

It will be assumed that the car is stationary at a floor with the car gate and hatchway door at that floor open and that the motor generator set is at rest. To start the motor generator set in operation, the start switch 150 within the car is closed. This causes the operation of starting relay M by connecting its actuating coil M 151 across alternating current mains 145 and 146 through knife switch 152, this knife switch being on the control panel for operation by the penthouse attendant. Relay M engages its contacts M 147 to connect coil K 148 of the starting switch across alternating current mains 144 and 145 through contacts L 149 of running switch L. Switch K operates to engage its contacts K 153, K 154 and K 155, connecting the stator windings of the driving motor to the alternating current mains through resistances 156, 157, and 158. Relay M also engages its contacts M 163 to connect coil L 162 of the running switch across the stator windings of the driving motor so that, as the driving motor comes up to speed and the voltage applied to coil L 162 increases to a certain value, switch L operates to engage its contacts L 159, L 160 and L 161. This connects the driving motor directly to the alternating current mains. Switch L also separates its contacts L 149 to deenergize coil K 148 of starting switch K, disconnecting resistances 156, 157 and 158. Switch L is provided with additional contacts L 25 and L 54. Contacts 90 95 100 105 110 115 120 125 130

L 54 are arranged in the circuit with the actuating coil A 53 of the potential switch, and their purpose will be explained later. Contacts L 25 are arranged in shunt to the actuating coil J 27 of the minimum current field relay. Coil J 27 is arranged in series relation with the elevator motor field winding 23.

The E. M. F. of the exciter builds up to its full value as the driving motor comes up to full speed. As has been previously stated, the exciter supplies current to the field winding 23 of the elevator motor. However, since contacts L 25 do not separate until the driving motor approaches full running speed, the coil J 27 does not receive current until the exciter E. M. F. is built up to substantially full value.

Furthermore, until the elevator motor field builds up to substantially full value, this field having a certain time constant, the current supplied to coil J 27 is of insufficient value to cause the operation of relay J. As soon as the elevator motor field builds up to substantially full value, relay J operates to engage its contacts J 55 in the circuit for coil A 53 of the potential switch. This completes the potential switch actuating coil circuit, the circuit being through potential switch contacts A 51 and safety switch 56 in the elevator car. Thus, the operation of the potential switch is prevented until the exciter E. M. F. has built up substantially to full value and until the elevator motor field has built up to substantially full value.

The potential switch operates to engage its contacts A 57 and A 58, preparing the circuit for the generator separately excited field and various control circuits. Potential switch A also separates its contacts A 51 to insert a cooling resistance 52 in series with actuating coil A 53. This is the condition of the circuits with the motor set in operation and the elevator car stopped at a floor with the door and gate open.

Assume that the car gate and hatchway door are closed. To start the car, the car switch is moved out of neutral position, the direction of movement depending on the direction of car travel desired. Assume that it is desired to start the car in the up direction. The car switch is moved in a direction to cause its segment 90 to bridge stationary contacts 89 and 91. This completes a circuit for actuating coil B 88 of the up direction switch and actuating coil H 94 of the brake switch through door contacts DC 92 (a single set of contacts being illustrated in lieu of the several pairs of door contacts connected in series relation), gate contacts GC 93, down direction switch contains C 87 and safety switch 56. Switch B operates to engage its contacts B 119 and B 131. This completes a circuit for the generator separately excited field winding 123 through resistances 117 and 118 and actuating coil G 122 of the maintaining relay.

Switch B also engages its contacts B 101 to prepare a circuit for auxiliary coil B 102 for the up direction switch and auxiliary coil H 105 for the brake switch and separates its contacts B 96 in the circuit for actuating coil C 97 of the down direction switch. Switch H operates simultaneously with switch B to engage its contacts H 108, completing a circuit for the brake release coil 112 through contacts 110 in a position to be operated by the brake mechanism. Switch H also separates its contacts H 125 to disconnect the generator field winding 123 from across the generator armature 127.

Voltage being applied to the generator field winding 123 and the brake release coil 112 being energized to release brake 113, the elevator motor starts the car in the up direction. The brake, upon being released, effects the separation of contacts 110 to insert cooling resistance 109 in circuit with brake release coil 112.

Switch H is provided with additional contacts H 80 which engage to prepare a circuit for the actuating coil E 77 of the first accelerating switch. This circuit is completed upon car switch segment 90 engaging contact 81 and is through resistance 69, inductance coil X 73 and safety switch 56. The operation of switch E is delayed due to the action of inductance coil X 73. Upon operation, switch E engages its contacts E 114 to short-circuit a step of generator field resistance 117. This increases the voltage applied to the generator separately excited field winding, thus increasing the generator voltage and the speed of the elevator motor. Switch E also engages its contacts E 107 to complete the circuit for the auxiliary coils B 102 and H 105 of the up direction switch and brake switch respectively. Switch E is provided with additional contacts E 75 which engage to prepare a circuit for the actuating coil F 74 of the last accelerating switch. This circuit is completed by the engagement of car switch segment 90 with stationary contact 76 and is through resistance 69, inductance coil X 73 and safety switch 56. The operation of switch F also is delayed by the action of inductance coil X 73. Upon operation, switch F engages its contacts F 116 to short-circuit the remaining step of generator field resistance 117. This increases the excitation of the generator field winding to full value, increasing the generator voltage and the speed of the elevator motor.

Switch F also separates its contacts F 29 in shunt to resistance 32 in the circuit for the elevator motor field winding 23. The separation of these contacts has no effect at this time inasmuch as contacts Z 30 of the speed regulating switch Z are engaged. The actuating coil Z 129 of switch Z is connected across the generator armature 127 so as to be subject to generator voltage and is set to cause the

operation of switch Z upon the generator voltage increasing to substantially full value. Upon operation, switch Z separates its contacts Z 30 to insert resistance 32 in circuit with elevator motor field winding 23. This weakens the elevator motor field causing the elevator motor to increase its speed to full value.

The starting of the car in the down direction is accomplished in a similar manner and need be only briefly described. The car switch is moved in the opposite direction to cause the engagement of segment 90 with contacts 95, 98, 99 and 100. The actuating coil C 97 of the down direction switch C is energized instead of that of the up direction switch. This switch is provided with an auxiliary coil C 104 and contacts C 130, C 120, C 103 and C 87 corresponding respectively with coil B 102 and contacts B 119, B 131, B 101 and B 96 of the down direction switch. It is to be noted that the circuit for coil C 97 passes through contacts B 96 of the up direction switch while the circuit for coil B 88 passes through contacts C 87 of the down direction switch. These contacts serve as electrical interlocks as is understood in the art. Mechanical interlocks may also be provided on the direction switches as indicated in Figure 3. The other circuits and operations incident to starting the car in the down direction are believed obvious from previous description.

It is to be noted that the car switch may be thrown to full on position in either direction rather than moved in steps in which event sequence in the starting operations is insured by the action of inductance coil X 73 and the interlocks provided by contacts H 80 and contacts E 75.

To stop the car, the car switch segment may either be returned immediately to off position or may be returned to off position in steps. As it is believed that the operation of stopping the car by a step-by-step return of the car switch will be obvious from the description of stopping the car by the immediate return of the car switch segment to neutral, the latter operation will be described. Assuming operation in the up direction, the return of the car switch segment to neutral breaks the circuit for coils F 74, E 77, B 88 and H 94 of the accelerating switches F and E, up direction switch B and brake switch H respectively.

Switch F drops out immediately, causing the reengagement of its contacts F 29 and the separation of its contacts F 116. Contacts F 29 short-circuit resistance 32, increasing the elevator motor field strength to full value for the slow down operation. The separation of contacts F 116 reinserts a step of resistance 117 in circuit with generator field winding 123. This reduces the excitation of the generator and therefore the gen-

erator voltage, reducing the speed of the elevator motor.

Switch E does not drop out immediately, its action being delayed by the effect of inductance coil X 73 and discharge resistance 86. 70 Switch E, upon returning to deenergized position, separates its contacts E 75, E 114 and E 107. Contacts E 75 are in circuit with coil F 74, switch F having already returned to deenergized position. Contacts E 114 rein- 75 sert the remaining step of resistance 117 in circuit with the generator field winding 123. This further reduces the excitation of the generator and therefore the generator voltage, bringing the elevator motor down to 80 slow speed.

Switches B and H do not drop out on deenergization of their actuating coils B 88 and H 94, they being maintained in operated condition by auxiliary coils B 102 and H 105. 85 Contacts G 106 of the maintaining relay G are arranged in parallel with contacts E 107 in circuit with auxiliary coils B 102 and H 105 so that these coils are maintained energized so long as either contacts E 107 or contacts G 106 are in engagement. The actuating coil G 122 of maintaining relay G is in circuit with the generator field winding 123 and is set to cause the engagement of contacts G 106 when the generator field builds 90 up to a certain value. The rate at which the generator field strength decreases during retardation is controlled by discharge resistance 121 and therefore the rate at which the current in coil G 122 decreases during retardation is also controlled by discharge resistance 121. The auxiliary coils B 102 and H 105 are therefore maintained energized during slow down of the elevator motor until switch E separates its contacts E 107 and 105 until the generator field strength has decreased to a sufficiently low value at which the current in coil G 122 is no longer capable of maintaining contacts G 106 in engagement.

Upon deenergization of auxiliary coils B 102 and H 105, the up direction switch and brake switch return to deenergized positions. Switch B separates its contacts B 119 and B 131, disconnecting the generator field winding from the exciter and switch H separates its contacts H 108, deenergizing brake release coil 112. Thus, the generator field being disconnected from the exciter and the brake release coil being deenergized, the application of the brake 113 brings the elevator motor to a stop. Switch B also separates its contacts B 101 in the circuit for auxiliary coils B 102 and H 105 of the up direction switch and brake switch respectively and separates its contacts B 96 to prepare the circuit for the down direction switch coil C 97. 115 Switch H also separates its contacts H 80 in circuit for coil E 77 of accelerating switch E and reengages its contacts H 125 to reconnect generator field winding 123 across the gener- 120 125 130

ator armature 127. The connection of generator field winding 123 to the generator armature by contacts H 125 is of such polarity as to send current through field winding 123 in such direction as to oppose the flux which produced the generator E. M. F., thus tending to destroy the residual flux of the generator field.

10 A governor is provided and arranged to be operated at a speed corresponding to that of the elevator motor. This governor is provided with contacts designated 26 arranged in shunt to elevator motor field resistance 32. These governor contacts close to short-circuit 15 this resistance in the event that the motor overspeeds above a certain amount, thus increasing the elevator motor field strength, thereby reducing the speed of the elevator motor.

20 A safety switch 56 is arranged in the car and is employed to stop the car under emergency operating conditions. The pulling of this switch deenergizes actuating coil A 53 of the potential switch, resulting in the disconnection of the generator field winding 25 from the exciter and the application of the brake to bring the elevator car to an immediate stop.

The driving motor may be stopped by opening start switch 150 in the car. This deenergizes the actuating coil M 151 of starting relay M. Relay M, in turn, separates its contacts M 163 to deenergize actuating coil L 162 of the running switch. The running switch 35 thereupon separates its contacts L 159, L 160 and L 161 to disconnect the stator windings of the driving motor from the alternating current mains.

In the above description, it was assumed 40 that the driving motor and elevator motor were started up after a period of shut-down, such as over night, and that the driving motor, generator, exciter, elevator motor and control apparatus were "cold". Assume, 45 however, that the temperatures of the windings of the drive units increase due to continuous operation. The driving motor, being of the alternating current induction type, is substantially unaffected by any increase in temperature of the stator windings or rotor bars so that this increase in temperature does not affect the speed of this motor. However, the heating of the windings of the generator and elevator motor affects the operation of the 50 system. The heating of the separately excited field winding 123 of the generator causes the resistance of this winding to increase and therefore cuts down the amount of current flow therethrough for a given application of 55 voltage. Similarly, the heating of the separately excited field winding 23 of the elevator motor causes the resistance of this winding to increase and therefore cuts down the amount of current flow therethrough for a 60 given application of voltage. The increased

resistance of the generator field winding results in a decrease in the voltage applied to the elevator motor armature for a given voltage applied to the generator field winding. Thus, this tends to decrease the speed of the elevator motor for a given load applied thereto. The increase in resistance of the elevator motor field winding decreases the elevator motor field strength, thus tending to increase the speed of the elevator motor for a given 75 load applied thereto. These two changes in resistance tend to counteract each other to provide constant speed of the elevator motor for a given load thereon but such counteraction is not sufficient to give the same operating speed as if the motor and generator were "cold" owing to the difference in characteristics of the generator and elevator motor and to the fact that the elevator motor field is energized all of the time that the elevator car is in service, whereas the generator field is deenergized when the elevator car is at a standstill. Furthermore, such decrease in the strength of the elevator motor field and generator field affects the torque of the elevator motor. The heating of the exciter, due to its continuous operation while the elevator car is in service, also affects the value of voltage applied to the generator and elevator motor field windings. Increased resistance of the exciter field, due to heating, weakens the field strength of the exciter and therefore its terminal voltage. Consequently, the voltage available for application to the generator and elevator motor field windings 90 increases, resulting in a further decrease in the voltage applied to the elevator motor armature and a further decrease in the field strength of the elevator motor. The resistance of the armatures of these various machines also changes due to heating, thereby further affecting the operation of the elevator motor. The effects of these resistance changes of the windings of the various machines may be obviated by the employment 100 of compensating resistances controlled in accordance with the principles of the invention. 105

In the control system illustrated, compensating resistance 33 is provided in series with the elevator motor field winding 23 and compensating resistance 118 is provided in series with the generator field winding 123. Each of these resistances is shown as arranged in three steps adapted to be successively short-circuited by compensating relays. The circuits for the actuating coils of these relays are controlled by the contact elements of a compensating mechanism unit, one for the elevator motor and one for the generator as 110 previously described.

115 As the elevator motor field winding heats up and its resistance increases, the fluid in bulb 24 expands, acting through the bellows device 40 to move contact segment 41 into engagement with stationary contact 44. 120

This completes a circuit for coil Q 45 of elevator motor compensating relay Q. This relay operates to engage its contacts Q 48, short-circuiting a step of resistance 33. The value of this step of resistance is such as to compensate for the increased resistance of the motor field winding 23 and the decreased voltage of the exciter. Upon further increase in the heating of the field winding 23, segment 41 is moved into engagement with contact 43 to energize coil R 46 of compensating relay R. This relay engages its contacts R 49 to short-circuit another step of resistance 33. Similarly, upon further heating of the elevator motor field winding and upon such winding reaching substantially its maximum temperature for the particular installation, coil S 47 is energized to effect the engagement of contacts S 50 of the third compensating relay S. This short-circuits the remaining step of resistance 33. The value of each of the last two steps of resistance 33 is chosen to give the desired compensation as in the case of the first step.

As the generator heats up, the compensating mechanism unit for the generator operates in a similar manner to effect the successive operation of relays N, O and P. As the fluid in bulb 124 expands, bellows device 143 moves lever 142 about its pivot to effect the successive engagement of segment 141 with contacts 140, 139 and 138. This causes the successive energization of coils N 135, O 136 and P 137. The energization of the coils causes the successive engagement of contacts N 132, O 133 and P 134 respectively to short-circuit compensating resistance 118 in steps. The values of these steps of resistance 118 are chosen so as to compensate for the decreased voltage of the exciter, the increased resistance of the generator field windings and the increased resistance of the elevator motor and generator armatures.

It is to be understood that the compensating mechanism units may be arranged to control the compensating resistance in any desired number of steps, three being shown merely for convenience of illustration.

With the compensating arrangement for the generator and elevator motor as above described, it will be seen that by proper selection of resistance values and proper adjustment of the compensating mechanism units, uniform operation may be obtained, regardless of the load in the elevator car, direction of travel of the car or temperature of the windings of the various drive units. That is, by the compensating arrangement for the elevator motor field winding, the field strength of the elevator motor may be maintained substantially constant, thus providing a constant field for the elevator motor, while by the compensating arrangement for the generator field winding the current flowing through the elevator motor armature may

be caused to be the same for the same load on the elevator motor. Thus, the torque of the elevator motor, which is proportional to the elevator motor field and armature current may be rendered independent of temperature conditions and uniform speed of the elevator motor obtained.

The arrangement of the compensating mechanism and resistances as above described also insures the same acceleration and retardation for the same load on the elevator motor. This is due to the fact that the torque is independent of temperature variations. In this connection, it is to be noted that compensating resistance 33 is arranged in the elevator motor field winding circuit in such a position so that it is effective to control the field strength of the elevator motor during acceleration and retardation as well as during full speed operation.

The accelerating mechanism may be utilized as an aid to obtaining uniform operations of the elevator car. This may be done by changing the timing of the accelerating switches by means of compensating resistance and compensating mechanism such as described for the generator and elevator motor field windings. Such arrangement of resistance and mechanism is illustrated in Figure 2 of the drawings wherein the bulb 78 containing the expandable fluid is arranged with the operating coil of accelerating switch E. It is to be noted that two compensating resistances are provided for coil E 77, resistance 69 being arranged in series relation with the coil and resistance 85 being arranged for connection in series with the discharge resistance 86 for the coil. Resistance 69 is also arranged in the circuit for the actuating coil of switch F so that this switch, as well as switch E, is controlled by the compensating mechanism for the acceleration.

In order that the manner in which the accelerating mechanism may be utilized to aid in obtaining uniform operation may be readily understood, assume, for example, that the compensating arrangement for the elevator motor field winding 23 is arranged

to provide compensation for full speed operating conditions. That is, resistance 33 may be made subject to contacts F 29 and contacts Z 30 so as to be maintained short-circuited until the car has been brought up to substantially full speed. In such case, the torque which the elevator motor is capable of developing for acceleration and retardation becomes less as the temperature increases.

Coincident with the heating of the elevator motor field winding, the coil of switch E also heats up through numerous periods of energization so that the expanding fluid in bulb 78 acts through tube 68 to cause bellows device 67 to move lever 66 into position where its contact segment 65 engages contact 64. This energizes coil V 61 of compensating relay V.

Relay V operates to engage its contacts V 72 and to separate its contacts V 84. This short-circuits one step of resistance 69 and inserts a step of resistance 85 in series with discharge resistance 86. The value of the step of resistance 69 is such as to provide quicker operation of switches E and F during acceleration. The insertion of the step of resistance 85 in the discharge circuit for coil E causes switch 10 E to return more quickly to deenergized position during retardation. A similar effect is had upon engagement of segment 65 with contacts 63 and 62 to energize coils U 60 and T 59. Contacts U 71 and T 70 short-circuit 15 additional steps of resistance 69, contacts U 83 and T 82 insert additional steps of resistance 85 in the discharge path of coil E 77. The quicker operation of accelerating 20 switches during acceleration and retardation as described compensates for the tendency of the elevator motor to develop less torque as the resistance of its field winding increases. It is to be understood that resistance 85 and contacts T 82, U 83 and V 84 may be omitted 25 if the desired timing of switch E in dropping out is obtained as a result of the increased resistance of its coil due to heating.

The accelerating mechanism compensating arrangement may be employed as an aid to 20 obtain uniform operation with compensating resistance 33 for elevator motor field winding 23 arranged in the position illustrated inasmuch as it may be employed to correct any errors present due to adjustments of the other 25 compensating arrangements. The accelerating mechanism compensating arrangement may also be employed alone, if desired, to control acceleration and retardation. In any of these arrangements, by employing a greater 30 number of accelerating switches controlled by the compensating mechanism, very satisfactory compensation can be obtained.

The accelerating mechanism compensating arrangement may also be employed to maintain 45 a constant timing of the accelerating switches, should the heating of the coils of these switches be sufficient to cause enough change in their impedance to vary the timing. Such arrangement may be utilized 50 either with or without the compensating arrangement shown in Figure 2 for the elevator motor field winding and generator field winding. In a system in which compensation such as shown is provided for the generator 55 and elevator motor field windings and in which the timing of the accelerating switches tends to vary due to temperature changes, the employment of temperature compensating mechanism to maintain the timing of the 60 accelerating switches constant insures the same acceleration and retardation for the same load on the elevator motor. In the event that the compensating accelerating mechanism arrangement is employed for this 65 purpose, contacts T 82, U 83 and V 84 and

resistance 85 may be omitted and the discharge circuit for coil E 78 connected to include resistance 69. The value of resistance 69 would be made such as to give the desired timing of the accelerating switches under 70 conditions where the system was started up "cold". Thus, as the temperature of coil E 77 increases, the steps of resistance 69 would be cut out in sequence. The values of these 75 steps would be such as to compensate for the change in resistance of coils E 77 and F 74 so that the timing of these switches in pulling in remains the same and the timing of switch E in dropping out also remains the same. 80

The compensating arrangement might also be employed to vary the value of inductance of coil X 73, if desired.

It is to be noted that coil F 74 is not subject to the compensating mechanism in the dropping out of switch F inasmuch as it is usually desired to have the last accelerating switch drop out immediately the circuit for its coil is broken. The compensating arrangement for the accelerating mechanism arranged to 90 provide uniform acceleration and retardation as above described is particularly useful in systems wherein the starting of the car is controlled by a single operation, as for example in the system illustrated, by throwing 95 the car switch immediately to full on position. The retardation compensation obtained is particularly useful in systems such as described under conditions where the stopping of the car is effected by returning the 100 car switch immediately to neutral position.

In the control system illustrated, only two accelerating switches are shown. It is to be understood, however, that any number of accelerating switches may be employed depending upon the requirements of the particular installation. Also, other types of accelerating mechanism may be utilized, for example, a motor operated rheostat in which the operating motor runs in one direction for 110 the accelerating operation and in the other direction for the retarding operation. With such arrangement, the compensating resistances, relays and associated mechanism may be arranged to control the value of resistance of the motor field circuit and the bulb placed within the operating motor so as to 115 correctly register temperature changes therein. 120

In the event that the compensating arrangement for the accelerating mechanism is employed to vary the acceleration and retardation, the bulb for bellows device 67 may be positioned at some other point, as for example in the elevator motor. The compensating arrangement for the accelerating mechanism may be omitted entirely and the desired operation obtained by proper 125 adjustments of the compensating arrangements 130

for the elevator motor and generator field windings.

Compensating mechanism may also be provided for the exciter, if desired. Such arrangement is shown diagrammatically in Figure 4. Only a portion of the circuits is shown in this figure as it is believed that this is sufficient in view of the previous description. In this figure, the compensating resistance for the exciter field winding is designated 175 and the contacts of the compensating relays for controlling this resistance are designated 176, 177 and 178. The operating coils of the compensating relays are not shown in this figure, nor are the compensating mechanism units shown. It is to be understood, however, that the bulb for the exciter compensating mechanism may be arranged in the exciter, a bulb designated 179 being illustrated in this figure as arranged in the exciter shunt field winding 21. The compensating relays for the exciter are actuated as the exciter temperature increases to successively short-circuit the steps of compensating resistance 175. These steps may be adjusted to provide constant terminal voltage of the exciter so that the steps of resistance 33 for the elevator motor field winding 23 may be adjusted to maintain uniform resistance of the elevator motor field winding circuit and the steps of resistance 118 for the generator field winding may be adjusted to compensate for increase in resistance of the generator field windings and generator and elevator motor armature windings.

The principles of the invention are also applicable to systems in which a direct current driving motor is employed for driving the generator. Such arrangements are illustrated in Figures 5 and 6 of the drawings. Both Figures 5 and 6 are diagrammatic as in the case of Figure 4. In both Figures 5 and 6, the driving motor armature is designated 180, its series field winding 181 and its shunt field winding 182.

In Figure 5, compensating mechanism is employed for the driving motor. The bulb 187 of the driving motor compensating mechanism is illustrated as positioned in the field winding 182. The compensating resistance for the driving motor is designated 183 and is arranged in series with field winding 182. The contacts of compensating relays for resistance 183 are designated 184, 185 and 186. The compensating mechanism acts, in the arrangement illustrated, to short-circuit steps of compensating resistance 183 as the driving motor heats up. In this manner, the driving motor speed may be maintained constant, regardless of temperature variations in the motor. In such case, the steps of compensating resistance 118 for the generator field winding may be made such as to compensate for changes in resistance of the generator field windings and generator and elevator

motor armature windings while the steps of compensating resistance 33 for the elevator motor field winding may be made such as to provide a uniform field for the elevator motor.

In Figure 6, compensating mechanism is provided for only the generator and elevator motor. Thus, in such arrangement, upon the driving motor becoming heated, its speed increases due primarily to the increased resistance of its field winding 182 and consequent weakening of its field. Thus, the generator speed becomes higher and the generator voltage tends to increase. Owing to the fact that the generator field winding 33 is not energized all the time, due to numerous periods in which the elevator car is at rest at the various landings, the compensating relay contacts N 188, O 189 and P 190 for generator field compensating resistance 33 118 may be arranged as breaking contacts to insert steps of resistance in circuit with the generator field winding as the temperature of the generator increases. In this manner, the generator field is weakened so as to cause the generation of desired voltage for application to the elevator motor armature. In such case, the compensating arrangement for the elevator motor would be the same as described for Figure 5.

In both Figures 2 and 6, arrangements are illustrated in which compensating mechanism for one of the drive units is omitted. Satisfactory operation may be obtained for certain installations by other arrangements. For example, in Figure 4, the compensating arrangements for both the generator field and elevator motor field may be omitted and the steps of compensating resistance 175 arranged so as to permit an increase in the value of exciter voltage as the temperature increase takes place. By proper choice of resistance steps 175, substantially uniform operation of the elevator motor may be obtained. This is due to the fact that as the resistance of the generator and elevator motor field windings increases, the exciter voltage increases, thereby increasing the voltage applied to these windings.

Although the invention has been described in connection with temperature rises due to operation of the various drive units, the compensating mechanism acts to provide compensation regardless of the cause of the temperature increases. Thus, any increase in room temperature sufficient to tend to vary the operation of the elevator motor is compensated for. Furthermore, the compensating mechanism operates to provide the desired compensation in the case of short periods of shut-down in which the various drive units do not return to "cold" condition or in case the system is started up under the conditions where the drive units are not "cold" due to other causes, such as seasonal

temperatures. Also, the individual compensating mechanism units may be arranged to provide the desired compensation in cases where the temperature changes in one or more of the drive units is different from that of the others due to the location of these units in the penthouse or due to draughts or other causes.

The principles of the invention are also applicable to other types of drive for the elevator car such as resistance controlled elevator motors, multi-voltage systems or any similar type of electric drive in which variation in operating conditions is likely to be obtained due to temperature changes. The temperature compensating mechanism unit is only diagrammatically illustrated for the reason that it is desired to illustrate only the principles of the invention inasmuch as the construction of the compensating apparatus may be considerably varied. Various expandible fluids may be employed or other temperature sensitive devices may be used. The mechanism to which the temperature changes are relayed to control the compensating resistance also may be varied. A single compensating mechanism unit may be employed for more than one unit of the system. The positions of the bulbs may be varied. Other compensating resistance arrangements may be employed such as parallel resistances or combination series and parallel resistances. Also, the compensating resistances may be arranged in parallel with the windings in conjunction with series resistance. In fact, any form of mechanism which compensates for changes in resistance of windings of an electric drive unit or units in accordance with temperature changes to which such winding or windings are subjected may be employed without departing from the spirit of the invention.

The compensation for temperature changes in accordance with the principles of the invention may be very effectively employed in conjunction with other compensating arrangements, such as those for compensating for variation in loads on the elevator motor. A generator series field winding has been illustrated as means for effecting load compensation. Other arrangements may be employed, however, either in lieu of or in conjunction with the series field winding.

In the control system illustrated, the starting and stopping of the car is effected by operation of a car switch to on and off position. The control system illustrated is chosen merely for convenience of description and it is to be understood that the principles of the invention are also applicable to other elevator systems, such as those in which push button control is employed to cause both the starting and stopping of the car or for causing only the stopping of the car, or to those in which the starting of the car is under the control of

an operator while the slow down and stopping is automatic. In systems in which the slow down and stopping of the car at the various landings is automatic, the dropping out of the accelerating switches may be controlled in accordance with the position of the car. In such event, no compensating mechanism would be employed for timing the dropping out of the accelerating switches. In case some of the accelerating switches are not controlled in accordance with car position in the slow down and stopping operation, the compensating mechanism may be employed to control the timing of these particular switches in dropping out if desired.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In combination, an elevator car, a source of electrical power, mechanism for transforming the electrical power from said source into mechanical power for raising and lowering said car, said mechanism comprising a dynamo-electric machine, a resistance for controlling the operation of said machine, and means responsive to the temperature of a winding of said machine for so varying said resistance as to cause uniform operation of the elevator car.

2. In combination, an elevator car, a hoisting motor therefor having a field winding, a source of current for said winding, means for controlling the supply of current from said source to said winding, and means responsive to temperature changes of said winding for so controlling said first-named means as to maintain uniform current flow through said winding.

3. In combination, an elevator car, a source of electrical power, mechanism for transforming the electrical power from said source into mechanical power for raising and lowering said car, said mechanism comprising a dynamo-electric machine, a winding for controlling the operation of said machine, and means for causing uniform operation of said car, said last-named means comprising means responsive to different temperatures of said winding for compensating for changes in the value of the resistance of said winding incident to said different temperatures.

4. In combination, an elevator car, a source of electrical power, mechanism for transforming the electrical power from said source into mechanical power for raising and lowering said car, said mechanism comprising a dynamo-electric machine having a winding, a resistance for controlling the

- amount of current supplied to said winding, means for causing uniform operating conditions of said car regardless of variations in the value of the resistance of said winding 5 incident to temperature changes of said winding, said means comprising means responsive to the temperature of said winding for varying said resistance. 70
5. In combination, an elevator car, a hoisting motor therefor, a separately excited field winding for said motor, a source of current for said field winding, a resistance electrically connected to said field winding, and means operable in response to the temperature changes in said field winding to vary said resistance in such a manner as to cause the same amount of current to be supplied to said winding from said source during each 15 operation of said motor at a certain speed, regardless of any tendency of said current to vary due to temperature changes. 75
6. In combination, an elevator car, a hoisting motor therefor, a separately excited field winding for said motor, a source of current 20 for said field winding, resistance connected to said winding, and means operable in response to temperature changes in said winding to vary said resistance at a rate dependent upon the rate of change in value of the 25 resistance of said winding incident to the flow and discontinuation of the flow of current therethrough to maintain a uniform flow of current through said field winding. 80
7. In combination, an elevator car, a hoisting motor therefor, a separately excited field winding for said motor, a source of current 30 for said motor, a resistance in circuit with said field winding, relays for varying said resistance and means responsive to different 35 temperatures of said field winding for causing operation of said relays to vary said resistance in such manner as to provide uniform operation of the elevator car. 103
8. In combination, an elevator car, driving 40 mechanism for said car, said mechanism comprising a dynamo-electric machine having a winding, a resistance for controlling the amount of current to said winding, means for varying said resistance, and temperature controlled means for causing the variation of 45 said resistance by said resistance varying means to be such as to compensate for variations in the value of the resistance of said winding incident to changes in temperature 50 of said winding. 110
9. In combination, an elevator car, a hoisting motor therefor, a generator for supplying current to said motor, means for driving said generator, a separately excited field 55 winding for said motor, a separately excited field winding for said generator, a source of current for each of said field windings, and means for causing uniform operation of the elevator car, regardless of variations in the 60 value of the resistance of the windings of said 115
- generator and motor incident to temperature changes thereof, said means comprising resistance connected to each of said field windings and temperature controlled means for varying said resistances. 70
10. In combination, an elevator car, a hoisting motor therefor, a generator for supplying current to said motor, means for driving said generator, separately excited field windings for said motor and generator, a source of current for each of said field windings, a resistance in circuit with said motor field winding, a resistance in circuit with said generator field winding, and means responsive to the temperature of each of said field windings for varying said resistance for that winding to compensate for the changes in the value of the resistance of such winding incident to temperature changes thereof. 80
11. In combination, an elevator car, a hoisting motor therefor, a generator for supplying current to said motor, means for driving said generator, a separately excited field winding for said motor, a separately excited field winding for said generator, a source of current for each of said field windings, a resistance in circuit with said motor field winding, a resistance in circuit with said generator field winding, and means responsive to the temperature of said field windings for varying said resistances in such manner as to cause the amount of current supplied to said motor field winding and the voltage applied to said motor by said generator for each operation of the elevator car at full speed to be 95 such as to provide uniform operation of the elevator car, irrespective of the temperature changes to which the windings of said generator and motor are subjected. 103
12. In combination, an elevator car, a switching mechanism for controlling the operation of said car, said switching mechanism having a winding, and means responsive to temperature changes of said winding for controlling the operation of said switching mechanism. 105
13. In combination, an elevator car, a hoisting motor therefor, switching mechanism for controlling the acceleration of said motor, and means responsive to temperature changes affecting the operation of said motor for controlling the operation of said switching mechanism in such manner as to compensate for such effect of said temperature changes. 110
14. In combination, an elevator car, a hoisting motor therefor, switching mechanism for controlling the acceleration and retardation of said motor, and temperature responsive means for controlling the operation of said switching mechanism in such manner as to provide uniform acceleration and retardation of said motor, regardless of temperature changes affecting acceleration and retardation. 120
15. In combination, an elevator car, a hoist- 125

ing motor therefor, a plurality of electromagnetic switches for controlling acceleration and retardation of said motor, each of said switches having an actuating coil, circuits for said coils, means for varying the impedance of said circuits, and means responsive to temperature changes affecting the operation of said motor for varying said impedance.

16. In combination, an elevator car, a hoisting motor therefor, a plurality of electromagnetic switches for controlling acceleration and retardation of said motor, and means responsive to temperature changes affecting the operation of said motor for varying the timing of said switches.

17. In combination, an elevator car, a hoisting motor therefor, a generator for supplying current to said motor, means for driving said generator, a separately excited field winding for said generator, a source of current for said field winding, switching mechanism for varying the amount of current supplied to said winding from said source, and temperature controlled means for controlling the timing of said switching mechanism.

18. In combination, an elevator car, a hoisting motor therefor, a winding for said motor, a source of current for said winding, means for controlling the supply of current to said winding from said source, means responsive to different temperatures of said winding for so controlling said first-named means as to compensate for variations in the value of the resistance in said winding incident to temperature changes thereof, means for effecting a change of speed of said hoisting motor, a winding for said last-named means, a source of current for said last-named winding, means for controlling the supply of current to said last-named winding from said last-named source, and means responsive to different temperatures of said last-named winding for so controlling said means for controlling the supply of current to said last-named winding as to compensate for variations in the value of the resistance in said last-named winding incident to variations in the temperature thereof.

19. In combination, an elevator car, a hoisting motor therefor, said motor having a field winding, an exciter for supplying current to said winding, means for driving said exciter, and means responsive to different temperatures of said exciter controlling the value of the voltage generated thereby for application to said winding.

20. In combination, an elevator car, a hoisting motor therefor, said motor having a field winding, an exciter for supplying current to said winding, means for driving said exciter, and means responsive to temperature changes affecting said exciter and said field winding for causing the current supplied to said field winding by said exciter to be maintained uniform, regardless of the effect of said tempera-

ture changes on the value of the voltage of said exciter and on the resistance of said winding.

21. In combination, an elevator car, a hoisting motor therefor, a generator for supplying current to said motor, a separately excited field winding for said motor, a separately excited field winding for said generator, an exciter for supplying current to said field windings, means for driving said exciter, and means responsive to the temperature changes affecting the operation of said motor for controlling the value of the voltage generated by said exciter for application to said field windings.

22. In combination, an elevator car, a hoisting motor therefor, a generator for supplying current to said motor, a separately excited field winding for said motor, a separately excited field winding for said generator, an exciter for supplying current to said field windings, means for driving said exciter and said generator, a resistance in circuit with said motor field winding, a resistance in circuit with said generator field winding, and means responsive to temperature changes affecting the value of the exciter voltage, the value of generator voltage and the value of the field strength of the motor for causing the current supplied to said field windings by said exciter to be of such value as to cause uniform field strength of said motor and uniform current conditions of the motor armature, regardless of change in temperature affecting the voltage of the exciter, the field strength of the motor and the voltage of the generator.

23. In combination, an elevator car, a hoisting motor therefor, a winding for controlling the operation of said motor, a resistance for controlling the value of current supplied to said winding, switching mechanism for varying said resistance, and thermal means positioned to be subject to temperature changes affecting the operation of said motor for controlling the operation of said switching mechanism to vary said resistance.

24. An elevator system comprising, a plurality of elevator cars having substantially the same periods of operation and operating for substantially the same length of time during such periods, a hoisting motor for each car, a winding for each motor for controlling the operation thereof, and means responsive to temperature changes of said winding for one of said motors for controlling the flow of current in all of said windings in such manner as to compensate for temperature changes affecting the operation of said motors.

In testimony whereof, I have signed my name to this specification.

EUGENE WILSON YEARSLEY.
